UNITED STATES PATENT OFFICE.

BOONE V. H. JOHNSON, OF ST. LOUIS, MISSOURI, ASSIGNOR TO COMMONWEALTH STEEL COMPANY, OF GRANITE CITY, ILLINOIS, A CORPORATION OF NEW JERSEY.

RAILWAY TRUCK.

Application filed January 18, 1926. Serial No. 81,903.

My invention relates to an improvement in railway trucks and has for its object the improved cushioning of the load with reference to the wheels.

5 *Drawings.*

In the drawings—

- Fig. 1 is a plan view of a truck embodying my invention.
 10 Fig. 2 is a side elevation of the same, the side-wall being broken away and parts being shown in section.
 Fig. 3 is a plan view of the truck illustrating the location and arrangement of the 15 spring elements and equalizer bars when the auxiliary springs are omitted; e. g., as used in freight car or other purposes where the utmost resiliency or riding quality is unnecessary.
 20 Fig. 4 is a sectional view of the construction illustrated in Fig. 3, taken on the line 4—4 of Fig. 3.
 Fig. 5 is an end view of one of the hollow wheel pieces of the truck.

25 *Description.*

While I have illustrated the embodiment of my invention in a six-wheel truck, it is equally efficient in trucks of two wheels or 30 any multiple thereof.

The drawings depict a truck-frame A of usual construction, having at its sides hollow wheel-pieces B with depending pairs of pedestals 6—6 for the accommodation of journal-boxes 7, the top of each of said journal-boxes 7 having a vertically projecting rib 8 for contact or engagement with the lower face of the standard irregularly curved (or off-set) equalizer-bar 9 (see Fig. 2) or standard straight equalizer-bar 10 (see Fig. 4).

On top of these equalizer-bars 9 or 10, and interposed between said equalizer-bars 9 or 10 and the truck-frame A I provide my primary spring-elements C, here illustrated as 45 leaf-springs, each having a spring-band 11 fitting at its top loosely between lugs or stops 12—12 depending in pairs from the truck-frame A and serving to prevent longitudinal displacement of the spring-bands 11.

50 I provide any efficient anti-friction means, interposed between the ends (or one end) of the spring-elements C and the equalizer-bar 9 or 10 upon which it rides, and for that purpose have shown in the drawings fric-

tion-plates or wearing-plates 13—13 arranged in pairs.

My construction thus far described is the complete and efficient mechanism shown in Figs. 3 and 4, which furnishes ample resiliency and adequate weight and shock distribution for freight cars and the like. For passenger car service where the utmost riding quality is desired I employ an auxiliary spring-element D, here illustrated as a helical spring, interposed between the primary 65 spring element C and the equalizer-bar 9, its base being mounted on the bar 9 and its top carrying a grooved cap 14, the groove in which is arranged to receive the bottom of the spring-band 11. 70

My invention may be embodied in any form of truck-frame and may be modified and varied as to its structure and positioning in many ways without departure from my actual invention as defined in the claims 75 of this application.

Claims.

I claim:—

1. In a railway truck, a truck frame having journal-boxes; equalizer bars mounted on said boxes; semi-elliptic spring elements interposed between the truck frame and the equalizer bars, having sliding engagement with said equalizer bars; and helical spring 80 elements interposed between the semi-elliptic spring elements and the equalizer bars.

2. In a railway truck, in combination, a truck frame; journal boxes mounted in said frame; equalizers mounted on said journal boxes; leaf springs supporting the truck and contacting at their ends with said equalizers; and helical springs interposed between the said equalizers and said leaf springs. 90

3. In a railway truck, in combination; a truck frame having hollow wheel pieces; journal boxes mounted in said frame; equalizers supported on said journal boxes; leaf springs mounted upon said equalizers and having slideable engagement therewith, said 100 equalizers and leaf springs being mounted within said hollow wheel pieces; a spring band mounted on each of said leaf springs; spring elements interposed between said equalizers and said leaf springs, each of 105 said spring elements arranged to contact with the spring band of the opposing leaf spring.

4. In a railway truck the combination of spring elements interposed between the leaf a truck frame; journal boxes mounted in springs and the equalizer bars; and a grooved said frame; equalizers supported on said said cap mounted at the top of each of the last-
5 journal boxes; leaf springs supporting the named spring elements, its groove arranged weight of the frame and mounted upon said to receive the bottom of one of said spring 15
equalizers and having sliding engagement bands.
with said equalizers at one or both ends; In testimony whereof I have hereunto af-
a spring band mounted on each of said leaf fixed my signature.
springs; stops depending from the truck
10 frame and engaging said spring bands;

BOONE V. H. JOHNSON.
